UNITED STATES PATENT OFFICE.

HANS E. DANSTRUP, OF BROOKLYN, NEW YORK, ASSIGNOR OF ONE-HALF TO JOSEPH HARRISON, OF BROOKLYN, NEW YORK.

DOUBLE-ACTING RECIPROCATING PUMP.

Application filed October 11, 1922. Serial No. 593,845.

To all whom it may concern:

Be it known that I, HANS E. DANSTRUP, a citizen of the United States, residing at 1779 13th Avenue, in the borough of Brooklyn, in the county of Kings and State of New York, have invented certain new and useful Improvements in Double-Acting Reciprocating Pumps, of which the following is a clear and exact specification.

This invention relates to reciprocating pumps and my improvements are particularly directed to devices of this character wherein the cylinder is provided with ports which communicate with the interior thereof near its respective ends, these ports serving each as inlets and outlets in the reciprocating action of the piston.

With a pump organism thus characterized my invention includes a revoluble valve having passages arranged to coact with the cylinder ports for suction and discharge purposes, this valve being located intermediate the cylinder side which is provided with the ports and an outer wall or plate that is provided with liquid passages and ports, whose relative arrangement is such that the valve, in making a single revolution, representing out and in strokes of the piston, in one stroke serves to discharge the cylinder in advance of one of its ends, while filling the cylinder by suction at its other end, and on the return stroke operating reversely, the intake in each instance entering at one of the ports in the outer wall or plate, and the discharge, in each piston stroke being delivered through the other port in the outer wall or plate.

The revoluble valve is driven from the crank shaft which actuates the piston and consequently the direction of rotation of the valve reverses with the reversal of rotation of the crank shaft. In consequence, the passages in the revoluble valve are arranged to coact with the cylinder ports and the ports in the outer wall or plate in such manner that the direction of liquid flow through the ports in the outer wall or plate will vary according to the direction of rotation of the crank shaft.

Therefore the pump, having for example fixed pipes whereby it is in communication respectively with the hold of a vessel and a lighter may deliver liquid either to the hold from the lighter or to the lighter from the

hold according to the direction of rotation of the crank shaft.

Other features and advantages of my invention will hereinafter appear.

In the drawings:—

Figure 1 is a horizontal sectional view of a pump constructed according to my invention.

Fig. 2 is an end elevation thereof.

Fig. 3 is a side elevation thereof.

Fig. 4 is a section on the line 4—4 of Fig. 1.

Fig. 5 is a section on the line 5—5 of Fig. 1.

Fig. 6 is a section on the line 6—6 of Fig. 1, and

Fig. 7 is an enlarged sectional view of a packing ring.

In the example of my invention illustrated in the accompanying drawings, let 1 indicate a pump cylinder disposed horizontally and mounted on the base 2. Also a base 3 is shown as provided with bearings 4 in which is journalled a crank shaft 5, which connects, as by a pitman 6, with a piston rod 7 that operates through the cylinder head 8 and carries the piston 9 within the cylinder.

The cylinder is provided with the ports 10, 11 at one side thereof, these ports being disposed respectively near its opposite ends, this ported side of the cylinder being enlarged, as at 12, the enlargement having a flat outer surface 13.

An externally threaded annulus 14, having an inward flange 15, is screwed into a recess formed for its reception in the centre of enlargement 12, and a spindle 16, which has a head 17, engages thereby with the flange 15, and is extended outwardly from the annulus.

This spindle revolvably carries a valve 18 in the form of a flat disk, whose periphery is provided with gear teeth 19, which mesh with an intermediary gear 20, pivoted at 21, that is driven by a gear 22 carried by the shaft 5.

A valve head 23, in the form of a flat plate, is disposed at the outer side of valve 18, and is provided with a central orifice for the reception of spindle 16.

While the revoluble member 18 has been designated as the valve, actually the valve organism extends also through the mem-

ber referred to as the enlargement 12, and the member, referred to as the valve head 23, as will become apparent in the following description of these elements of the structure. But it is proper to state, at this juncture, that the fixed member 23 bears with elastic pressure against the revoluble member 18, which similarly engages the opposed surface 13 of fixed member 12. This engagement is shown as effected by means of four bolts 24 which respectively engage the lugs 25 extended equidistantly about the member 12, and are passed freely through corresponding lugs 26 extended from member 23; the ends of these bolts having adjustment nuts 27 which retain helical springs 28 that exert suitable tension against member 23, to thereby establish and maintain the operative relation of the valve elements.

It will be appreciated that by turning the nuts 27 the tension of springs 28 may be adjusted so as to permit proper freedom of rotation for member 18.

25 Packing rings 29, which may be of the lock character shown in Fig. 7, are placed in opposed grooves in the members 12, 18 and 23 to render their working surfaces liquid tight.

30 Also the spindle 16 is provided with an adjustment nut 30, and a spring 30^a lies between said nut and member 23, to hold the spindle suitably adjusted, while also exerting tension centrally with respect to the assemblage of the valve elements.

35 By reference to Fig. 5 it will be noted that the valve element 18 is provided with an arcuate slot or clearance 31, and an opposite, arcuate passage 32, of equal extent. The end walls 33 of the slot 31 are of convex form, and likewise the ends 34 of the passage 32 have convex form.

40 There is also a transverse, arcuate passage 36 in element 18 which communicates respectively with the opposite ends of passage 32.

45 Before relating the functions of the slot 31 and passages 32, 36, it will be proper to describe the passage in member 23 which is co-acts therewith. Therefore, attention is directed to Fig. 4 in which will appear the outer, arcuate passage 38 and the inner, opposed arcuate passage 39.

50 The passage 38, at its ends, communicates respectively with the ports 40, 41; and the passage 39, at its ends communicates respectively with the parts 42, 43.

55 The port 40 is in fixed alignment with the port 10 in the cylinder side, and the port 41 is in alignment with the port 11, which is also located in the cylinder side.

60 The operation of the device will be rendered clear by reference to Fig. 1, in which piston 2 is shown as making an outstroke, during which fluid is drawn into the cylinder,

65 behind the piston, through pipe A, passage 38, port 40, arcuate slot 31, and port 10. At the same time fluid is being expelled from cylinder 1, in advance of piston 2, through port 11, arcuate passage 32, transverse passage 36, passage 39, port 42 and out through pipe B.

70 The operation continues all through the out-stroke of the piston. On the return or in-stroke of the piston, or during the second half of the revolution of valve 18, when suction pull will be exerted at the forward face of the piston, the inlet will also be through pipe A, but its path will follow from port 41, through arcuate slot 31 and 75 port 11; and at the same time fluid will be delivered from the other side of the piston, through port 10, arcuate passage 32, transverse passage 36, arcuate passage 39, and out through pipe B.

80 In the foregoing operations it is assumed that the crank shaft, and consequently also the valve 18 are rotated in one direction. But if the rotation of the crank shaft and valve 18 be reversed, then the inflow to the cylinder will be through pipe B and the outflow from the cylinder through pipe A, as will be apparent.

85 Variations within the spirit and scope of my invention are equally comprehended by the foregoing disclosure:

I claim:

1. A pump comprising a cylinder, a reciprocating piston therein, a peripherally exposed, disc-like valve revoluble against one side of the cylinder in a plane parallel with the cylinder axis, tensional means to press said valve against the cylinder, and passage ways controlled by said valve to communicate with the cylinder at opposite sides of the piston during the respective entire strokes thereof, respectively for alternate outflow and inflow purposes according to the direction of piston movement.

2. A pump comprising a cylinder having ports at one side thereof respectively near its opposite ends, a reciprocating piston in said cylinder, a valve revoluble against the ported side of said cylinder in a plane parallel with the cylinder axis, and having an arcuate slot to co-act alternately with said ports during the respective entire strokes of the piston, and outer, fixed closure means having a passage way for communication with said arcuate slot.

3. A pump comprising a cylinder having ports at one side thereof, respectively near its opposite ends, a reciprocating piston in said cylinder, a revoluble valve operable at the ported side of the cylinder and having an arcuate slot, an arcuate passage opposed to the slot and a transverse passage in communication with the arcuate passage, said slot and arcuate passage respectively co-acting alternately with the ports, and outer,

fixed closure means having passage-ways respectively for communication with said slot and arcuate passage.

4. In a double acting pump, in combination, a cylinder having a piston reciprocable therein, one side of the cylinder having a plane surface and being provided with ports which communicate with the cylinder at opposite sides of the piston, a shaft extended from the ported side of the cylinder, a disk-like valve revoluble on said shaft, means for rotating said valve, and a fixed outer plate to enclose said valve, said outer plate having passage ways, and said valve having a slot and passage ways to alternately co-act between the respective cylinder ports and passage ways of the outer plate.

5. In a double acting pump, in combination, a cylinder having a piston reciprocable therein, one side of said cylinder having a plane surface and being provided with ports which communicate with the cylinder at opposite sides of the piston, a shaft extended from the port side of the cylinder, a disk-like valve revoluble on said shaft, an outer plate also mounted on said shaft to enclose said valve and having passage ways, said valve having a slot and passage ways to alternately co-act between the respective cylinder ports and passage ways of the outer plate, means to prevent rotation of the outer plate, and tensional means for pressing said outer plate against said valve and said valve against the cylinder.

35 6. In a double acting pump, in combination, a cylinder provided with ports near its opposite ends, a piston reciprocable therein, and a revoluble valve co-operative under spring tension with the cylinder ports during the entire strokes of the piston to sup-

ply and discharge the cylinder simultaneously, at opposite sides of the piston, in alternation.

7. In a pump of the character described, a cylinder having convertible inlet and exhaust ports, a piston reciprocating therein, a plate having substantially semicircular passages therein, one such passage being in communication with a source of fluid supply, the other passages being in communication with a destination for the pumped fluid, a rotary valve plate fitted between said cylinder and said first mentioned plate and having arcuate channels therein adapted to alternately register with the inlet and exhaust ports of said cylinder and with the passages in said first named plate, means for rotating said valve plate together with the reciprocating movement of the piston, and yieldable means acting on said first mentioned plate and on said valve plate for holding the same tightly together.

8. In a double acting reciprocating pump the combination of a cylinder having ports on opposite ends thereof, a piston within said cylinder, a valve rotatably mounted upon a fixed stud and having a toothed periphery, said valve being provided with an arcuate slot and with an arcuate recess oppositely disposed to said slot, and a valve plate held against rotation relative to said valve, and provided with oppositely disposed arcuate passages having different radii and having openings formed in said plate communicating with said passages.

Signed at the borough of Manhattan, in the city, county and State of New York, this 3rd day of October, 1922.

HANS E. DANSTRUP.
